FIG-3

FIG-4

FIG-5

FIG. 1 is a top perspective view of one end of a reflective bicycle pedal showing my new design.

FIG. 2 is a top perspective view of the other end thereof.

FIG. 3 is an elevational view of FIG. 1.

FIG. 4 is an elevational view as seen from the left end of FIG. 1.

FIG. 5 is an elevational view as seen from the right end of FIG. 1.

The characteristic feature of my design resides in the elongate reflective surfaces on the sides of the pedal.

I claim:

The ornamental design for a reflective bicycle pedal, as shown and described.
